(57) **CLAIM**

The ornamental design for a three wheel luggage base plate, as shown and described.

DESCRIPTION

FIG. 1 is a perspective view of a three wheel luggage base plate according to my new design;

FIG. 2 is a front elevational view thereof;

FIG. 3 is a right side elevational view with the left side being a mirror image thereof;

FIG. 4 is a top plan view thereof; and,

FIG. 5 is a bottom plan view thereof.

The broken line showing of luggage is for illustrative purposes only and forms no part of the claimed design.
